UNITED STATES PATENT OFFICE.

CHARLES H. WELLMAN, ALFRED ERNST, AND FREDELLIA H. MOYER, OF CLEVELAND, OHIO, ASSIGNORS TO THE WELLMAN-SEAVIER-MORGAN ENGINEERING COMPANY, OF CLEVELAND, OHIO, A CORPORATION OF OHIO.

COMBINED CHARGING AND DISCHARGING DEVICE FOR COKE-OVENS.

SPECIFICATION forming part of Letters Patent No. 731,251, dated June 16, 1903.

Application filed August 4, 1902. Serial No. 118,319. (No model.)

To all whom it may concern:

Be it known that we, CHARLES H. WELLMAN, ALFRED ERNST, and FREDELLIA H. MOYER, citizens of the United States, and residents of Cleveland, Ohio, have invented certain Improvements in a Combined Charging and Discharging Device for Coke-Ovens, of which the following is a specification.

Our invention consists of an improvement upon the coke-oven charging and discharging device forming the subject of Letters Patent No. 692,746, dated February 4, 1902, the object of our present invention being to simplify the construction of the pusher at the forward end of the movable bottom of the charging-hopper.

In the accompanying drawings, Figure 1 is a longitudinal section of a charging-hopper with pusher constructed in accordance with our invention, the parts occupying the position assumed when the hopper is being charged with coal. Fig. 2 is a similar section showing the parts adjusted for pushing the coke from the oven and carrying the fresh charge thereinto. Fig. 3 is a view similar to Fig. 2, but illustrating the position of the parts when the coke has been ejected from the oven and the fresh charge has been introduced into the same. Fig. 4 is a view similar to Fig. 3, illustrating the position of the parts when the movable bottom of the hopper is being withdrawn from beneath the charge of coal in the oven. Fig. 5 is a view similar to Fig. 1, but showing the position of the parts when the hopper-bottom and pusher have been fully withdrawn from the oven. Fig. 6 is an enlarged plan view of certain of the parts of the pusher occupying the relation shown in Fig. 1; and Fig. 7 is a perspective view showing part of the hopper, hopper-bottom, pusher, and end-closing plate, with the view of illustrating certain details of the same not clearly shown in the other views of the drawings.

1 represents the charging-hopper of a coke-oven-charging machine, and 2 the bottom of the same, to which longitudinal movement can be imparted by means of the devices shown in the patent before referred to or by

any other suitable devices, this feature of the machine forming no part of our present invention. The hopper-bottom has a forwardly-extending portion 3, to which is pivoted the lower end of the pusher-plate 4 and also one or more bars 5, which by preference carry a plate 6 of the full width of the hopper. In the present instance a pair of these bars is shown; but there may be more than two, if desired.

When the parts are in the position shown in Fig. 1—that is to say, during the time that the hopper is being charged with coal—the brace-bars 5 occupy a vertical position and the plate 6 closes the forward end of the hopper, the pusher-plate 4 in this case extending rearwardly at an angle from the forward end of the bottom extension 3 and serving to brace the bars 5, so as to prevent longitudinal displacement of the plate 6. When the hopper has received its load of coal, the position of the parts 4 and 5 is reversed, as shown in Fig. 2, the pusher-plate 4 being raised to vertical position and the bars 5 being inclined forwardly, so as to engage with a notch 7 in the back of the plate 4, and thus serve to brace the same against any rearward push which may be exerted upon it. The doors 8 of the coke-oven being opened, as shown in Fig. 2, the bottom 2 of the charging-hopper is moved forwardly and the pusher 4 acts upon the mass of coke in the oven to eject it therefrom, while at the same time the fresh charge of coal is being introduced into the oven. When this operation has been completed, the doors at the opposite ends of the oven are partly closed, so as to retain the mass of coal therein, as shown in Fig. 3, and both the pusher 4 and brace bar or bars 5 are lowered to a horizontal position preparatory to the withdrawal of the hopper-bottom 2, as shown in Fig. 4, the partially-closed rear door of the oven preventing any rearward movement of the mass of coal in the oven during this operation.

When the hopper-bottom has been completely retracted, as shown in Fig. 5, the doors of the oven are fully closed and the pusher 4 and brace 5 can then be restored to

the position shown in Fig. 1 prior to a repetition of the operation.

When the pusher-plate and its brace-bars are moved to horizontal position, the brace-bars overlap the pusher-plate to some extent, and the parts are mutually recessed, as shown at 9 and 10, to permit such overlap.

In Fig. 7 the pusher 4 is shown in the horizontal position in line with the projecting portion 3 of the bottom plate of the hopper and the hopper-closing plate 6 and brace-bars 5 are shown in the elevated position. In practice the parts never assume this specific relation to each other; but this disposal of them has been adopted in order to best illustrate the notches 7 and recesses 9 and 10.

Having thus described our invention, we claim and desire to secure by Letters Patent—

20 1. The combination of the movable hopper-bottom of a coke-oven-charging machine, with a pusher-plate and one or more brace-bars therefor, both the plate and its brace bar or bars being pivotally mounted upon the forward end of said hopper-bottom whereby they can be swung into horizontal position for withdrawal beneath the charge of coal in the oven, substantially as specified.

25 2. The combination of the movable hopper-bottom of a coke-oven-charging machine, with a pusher-plate and one or more brace-bars therefor, both the plate and the brace bar or bars being pivotally mounted upon the forward end of the hopper-bottom, said brace bar or bars having a plate for closing the forward end of the hopper, and the pivotal mounting of the pusher and brace being such that they can both be thrown down into hori-

zontal position for withdrawal beneath the coal in the oven, substantially as specified. 40

3. The combination of the movable hopper-bottom of a coke-oven-charging machine, with a pusher-plate and one or more brace-bars therefor, both the plate and the brace bar or bars being pivotally mounted upon the forward end of the hopper-bottom, said brace bar or bars having a plate for closing the forward end of the hopper, and the pivotal mounting of the pusher and brace being such that they can both be thrown down into horizontal position for withdrawal beneath the coal in the oven, and the pusher can also serve as a brace for the plate which closes the end of the hopper, substantially as specified. 45 50

4. The combination of the movable hopper-bottom of a coke-oven-charging machine, with a pusher-plate and one or more brace-bars therefor, both the plate and its brace bar or bars being pivotally mounted upon the forward end of said hopper-bottom whereby they can be swung into horizontal position for withdrawal beneath the charge of coal in the oven, the brace bar or bars overlapping the pusher-plate and the parts being mutually recessed in these overlapping portions, substantially as specified. 55

In testimony whereof we have signed our names to this specification in the presence of two subscribing witnesses.

CHARLES H. WELLMAN.
